UNITED STATES PATENT OFFICE

HELEN HALL SMITH, OF ST. LOUIS, MISSOURI

PATTERN

Application filed March 28, 1929. Serial No. 350,530.

My invention relates to patterns, particularly a pattern for use in making women's waists, coats and the like. The invention has for its principal object a pattern which is made to an individual's measurements and which can be used to make perfect-fitting garments of widely different styles. The invention consists principally in a pattern comprising parts that can be moved relatively to each other to produce different styles of garment all of which will fit properly; it also consists in the pattern and in the parts and combinations and arrangements of parts hereinafter described and claimed.

15 In the accompanying drawings,

Fig. 1 is a top plan view of a pattern embodying my invention showing the manner in which the pattern is originally laid out;

Fig. 2 is a bottom plan view with the parts 20 in the same relative positions as in Fig. 1, showing that certain of the parts of the pattern are connected by web-like members which are folded under to give the desired arrangement of the parts of the pattern:

25 Fig. 3 is a sectional view on the line 3—3 of Fig. 1;

Fig. 4 is a sectional view on the line 4—4 of Fig. 1;

30 Fig. 5 is a sectional view on the line 5—5 of Fig. 1;

Fig. 6 is a plan view showing the parts of the pattern arranged differently from Fig. 1;

Fig. 7 is a sectional view on the line 7—7 of Fig. 6;

35 Fig. 8 is a top plan view showing another arrangement of the parts of the pattern;

Fig. 9 is a sectional view on the line 9—9 of Fig. 8;

40 Fig. 10 is a top plan view showing a different arrangement;

Figs. 11 and 12 are top plan views showing still different arrangement of the parts of the pattern;

45 Figs. 13 and 14 are top plan views showing allowances to be made in cutting the coat or the like; and

Fig. 15 is a top plan view showing a slightly modified form of pattern.

50 In making women's waists and other garments, the principal difficulty is in making

the front of the garment fit, the back being comparatively easy to fit. The present invention deals with a pattern for the front of the garment and no pattern for the back portion is shown, as this can be easily made. 55 The pattern is made to the measurements of an individual and different garments are made by rearranging the portions of the pattern and by adding accessory portions, if required.

60 The pattern ordinarily comprises five parts:

The first part A extends from the center of the neck 1 downwardly to the bust line, thence along the bust line to the fullest point 65 of the bust 2, thence upward to the neck and along the curved neck line to the starting point.

The second part B extends from the shoulder 3 along the collar bone, stopping at a 70 point 4 several inches short of the neck, thence downwardly on a line 5 whose extension would touch the fullest point of the bust 2, thence along a line 6 parallel to the bust line and along the line defining the armhole 75 upwardly to the point of origin.

The third part C extends upwardly from the bust line a short distance to a point 7 under the arm, thence along a curved line 8 defining the arm opening until it meets the 80 lower edge of part B at a point 9 about four inches below the shoulders and thence along the lower edge of part B to the corner 10 thereof, thence downwardly as a continuation of the side 5 of part B until it reaches 85 the fullest point 2 of the bust and thence along the bust line.

The fourth part D extends downwardly from said third part to the waist line, its side edges being parallel and one corner being 90 disposed at the fullest point of the bust; and

The fifth part E extends downwardly from said first part to the waist line, one corner thereof being located at the fullest point 95 2 of the bust.

One edge of part E is a continuation of an edge of part A and in the making of the pattern the two edges extend vertically along the middle line of the front of the individual. In cutting certain garments (see Figs. 2, 7 100

and 8) part A may be swung out of this position. The parts of the pattern are arranged in different ways in cutting out different garments, but in each case parts A, C, 5 D and E meet at one corner, this point being the fullest point of one bust.

Ordinarily the several parts of the pattern are made of fairly heavy paper or the like and parts A, C, D and E are secured 10 together by web-like members K of tapering form, made of tissue paper or other thin material whereby the parts of the pattern are held permanently together and properly positioned about the meeting point 2 and the 15 parts may be opened out as desired to leave an opening or openings between parts of the pattern wherever required.

With the parts assembled as shown in Fig. 1, the connecting member between part A and 20 parts B and C is opened out to leave a triangular space 11 or dart portion between part A extending from the bust line to the neck and parts B and C extending from the bust line to the shoulder, parts A and E being disposed vertically. The other connecting 25 members are folded under as shown in Figs. 3 and 4, so that no space is left between parts A and E, D and E or C and D. With the pattern arranged in this way, it permits 30 the cutting of a waist with a dart on the shoulder, with gathers, shirrings, smocking or tucks on the shoulder.

As shown in Fig. 6, the portion of the pattern extending from the neck downwardly is 35 placed edge to edge with parts B and C, leaving a triangular opening 12 between part A and part E. This arrangement of parts is used in cutting a waist surplice style.

In Fig. 8, parts D, C and B, as a unit, are 40 swung around so as to reduce the size of the triangular opening 11 between part A and parts B and C and to make a triangular opening 13 between parts D and E. This arrangement of parts is used in cutting a garment 45 with fullness at the shoulder and also at the waist line.

In Fig. 10, the parts D, C and B are swung around still further so as to eliminate the 50 triangular opening 11 between parts A and parts B and C and make a large triangular opening 13' between parts D and E. This arrangement is used in cutting a garment 55 with fullness at the waist line only.

In Fig. 11 part B is separated from part 55 C and moved over against part A leaving a triangular opening 14 between parts A and C and also an opening 15 between parts B and C. This arrangement is used in cutting 60 a garment with fullness over the bust and with a fitted shoulder. In order to permit the arrangement of parts shown in Fig. 11 parts B and C can not be provided with a connecting member therebetween. However, 65 such arrangement is not generally used and

parts B and C may be made integral as shown in Fig. 15 being cut apart when needed.

In Fig. 12, a triangular opening 16 is left between parts C and D. This arrangement is used in cutting a garment that is tight- 70 fitting but has fullness under the arm.

Figs. 13 and 14 show the pattern used in cutting out coats. In this case, extra material must be left, as shown by the dotted lines to permit for overlapping of the parts of 75 the finished garment and also to give the desired length.

It will be understood that in cutting out garments, due allowance must be made for enough material to make a seam, that accessory features may be added as desired, that the material will ordinarily be cut double, so as to make both the right and left sides of the garment front, that the length may be whatever is desired for the garment, 85 that the skirt portion of the garment may be cut integral with the waist portion and that the back of the garment may be cut by any suitable pattern.

As previously stated, it is not ordinarily 90 necessary to make parts B and C adjustable relative to each other; and Fig. 15 shows a pattern having a single piece B', C' corresponding to the parts B and C of Figs. 1 to 14. Said Fig. 15 likewise shows a single 95 part A', D', E' corresponding to parts A, D and E of said Figs. 1 to 14. Tapering connecting web members K' are provided along the two sides of said part that are adjacent to said other part. In making most garments 100 this simpler form of pattern provides sufficient adjustments.

The above described pattern has numerous 105 advantages. Being made according to an individual's measurements, it provides a perfectly fitting garment, whereas patterns made according to so-called standard sizes are not likely to fit a particular individual. In using the pattern, it is very easy to add accessory 110 features to make the desired style of garment. However, in the case of inexpert seamstresses, a pattern may be obtained for the 115 accessory features and the body portions of such pattern corrected by the above pattern which was made for the individual. Likewise when readymade garments are purchased the above pattern affords an easy means of correcting the garment. Cases of misfitting ordinarily centers about the neck and shoulder portions of the garment or 120 about the bust; and by ripping open the garment and superimposing the pattern thereon, the incorrect features of the garment may be corrected.

Obviously the size and proportions of the 125 garment will vary with the size and build of the particular individual. It is noted also that nearly all styles of garments are made with the parts of the pattern disposed with parts 1 and 2 together and constituting, in 130

effect, a single piece. Accordingly, the pattern may be made with said parts 1 and 2 integral and still be capable of use in making most garments. Other changes may be made without departing from the invention and I do not wish to be limited to the precise construction shown.

What I claim is:

1. A waist pattern comprising at least three parts cornering on each other, the meeting point representing the fullest point of the bust, said parts being permanently secured together by means permitting shifting thereof without changing said meeting point.
- 15 2. A pattern comprising parts of relatively strong material cornering on each other at the bust and pieces of relatively weak material securing said pieces of strong material together, said pieces of weak material being shaped to maintain said cornering relation at the bust but to permit shifting of the parts of the pattern about their cornering portions.
- 25 3. A waist pattern made according to the measurements of an individual and comprising a plurality of parts cornering on each other at the bust of the individual, said parts being made so that tapering spaces are left between parts, said parts being movable so as to maintain said cornering relation but to change the size of said spaces.
- 35 4. A waist pattern made according to the measurements of an individual and comprising a plurality of parts cornering on each other at the bust of the individual, said parts being made so that a tapering space is left between at least two parts, said parts being movable so as to maintain said cornering relation but to change the size of said space.
- 40 5. A waist pattern made according to the measurements of an individual and comprising a plurality of parts cornering on each other at the bust of the individual, said parts being made so that a tapering space is left between two of said parts, one of said parts being movable so as to maintain said cornering relation but to change the size of said space and to make an additional space between said movable part and a third part.
- 45 50 6. A waist pattern made according to the measurements of an individual and comprising a plurality of parts cornering on each other at the bust of the individual, said parts being made so that tapering spaces are left between parts, said parts being movable so as to maintain said cornering relation but to change the size of said spaces.
- 55 60 7. A waist pattern made according to the measurements of an individual and comprising a plurality of parts cornering on each other at the bust of the individual, said parts being made so that a tapering space is left between at least two parts, said parts being movable so as to maintain said cornering relation but to change the size of said space

and to add another space between other parts of the pattern.

8. A waist pattern made according to the measurements of an individual and having a plurality of tapering adjustable dart portions extending from the point indicating the bust.

Signed at St. Louis, Missouri, this 23 day of March, 1929.

HELEN HALL SMITH.
